UNITED STATES PATENT OFFICE.

LESTER PRAHAR, OF NEW YORK, N. Y., ASSIGNOR TO LOUISE PRAHAR, OF NEW YORK, N. Y.

PORTABLE ELECTRIC LIGHT.

1,307,456.

Specification of Letters Patent. Patented June 24, 1919.

Application filed July 24, 1917. Serial No. 182,404.

To all whom it may concern:

Be it known that I, LESTER PRAHAR, a citizen of the United States, and a resident of New York city, in the county of New York and State of New York, have invented certain new and useful Improvements in Portable Electric Lights, of which the following is a specification.

This invention is a portable electric light so constructed that it may be worn on the back of the hand or wrist and used primarily for signaling purposes, although capable of other uses. The parts are so arranged and supported that the wearer may have full freedom of use of his hand, for instance, in shifting gears, steering or applying the emergency brake on an automobile, and while the circuit of the electric light is broken. The wearer may make or break the circuit of the light at will by a predetermined movement of the hand, such for instance, as would be natural or convenient in indicating to a driver of a car in the rear his intention of stopping or turning to one side or the other.

In its preferred embodiment, the light is energized by a small battery, the case of which serves as a base for the light so that the entire apparatus may be worn on the hand or wrist without attachment to any part carried by the car.

In the accompanying drawings, Figure 1 is an edge view of the device illustrated as clamped on the wrist and with the hand in such a position as to close the circuit;

Fig. 2 is a transverse section taken for instance on the line 2-2 of Fig. 3; and

Fig. 3 is a central longitudinal section taken for instance on the line 3-3 of Fig. 2. 40. In the specific form illustrated, I employ a casing made up of two parts 10 and 11 serving to contain and carry a battery 12. This battery may be of any ordinary commercial form of a size adapted for the purpose. In Fig. 2 I have not attempted to illustrate any of the plates or internal mechanism of the battery in the cross section there shown as said battery so far as the generation of current is concerned forms no portion of my invention.

The two parts 10 and 11 of the casing may be secured together in various different ways. Merely as an example, I have shown them each provided with a peripheral wall and the two walls arranged to telescope. Vari-

ous different means may be employed for holding the two parts of the casing together but a simple and inexpensive way is to utilize the same means which holds the casing on the wrist or hand of the wearer. As shown, the outer casing 10 has one of its peripheral walls provided with a slotted flange 13 to which a strap 14 may be permanently connected. Adjacent to this point of attachment is a buckle 15 while the body 65 of the strap extends across the bottom of the inner casing member 11 and through a corresponding and diametrically opposite slotted flange 16. The free end of the strap when attached to the buckle thus serves to 70 not only hold the two parts of the casing together, but to fasten it on the wrist or in any other desired position.

The outer or top wall of the casing 10 carries a small electric light 17. This may 75 be of a form commercially used in connection with small pocket flash lights and may have a threaded stem 18 screwed into the casing wall and terminating in a central contact member. The battery may be provided with a suitable spring contact member 19 with which the contact of the light will engage when the two parts of the casing are put together. The casing of the battery being of insulating material or 80 coated with such material, prevents the flow of current through the light until the other terminal of the battery is grounded on the casing. One end of the battery is provided with a spring contact member 20 and the 85 end wall of one of the casing members, for instance, the inner one may have a push button or any other suitable circuit closing device. This is shown as a plunger 21 normally held in outer position by a coil spring 95 and adapted to engage with the spring contact 20 and close the circuit when pressed inwardly. As an important feature of my invention, I so arrange and so design this circuit closing member that it may be operated by a particular movement of the hand in respect to the wrist. Preferably, this movement is a backward bending of the hand such as would be convenient or natural in indicating to a car in the rear 100 that you intend to stop. As shown, the battery casing is of such size and the push button is so positioned and of such length that when the hand is bent backward as illustrated in Fig. 1, the push button will 105 110

be forced inwardly to close the contact. The instant that the hand is bent back to forward or natural position, the circuit will be broken. Thus the hand may be freely used for any ordinary purpose without closing the circuit.

In case the wearer finds it inconvenient to have the strap 14 tightened so as to hold the battery against any sliding movement by the wrist such as would prevent the backward bending of the hand from closing the circuit, there may be provided additional securing means for preventing this sliding movement. For instance, a very narrow strap or cord 22 may have a loop at one end through which the middle finger may extend and at the other end may be secured to the strap as shown in Figs. 2 and 3. This might, for instance, be in the form of a small cord so that the distance between the loop and the point of attachment to the strap 14 could be varied at will to suit the convenience of the wearer.

In some commercial batteries as now manufactured there is a contact member similar in most respects to the contact member 20 and an additional contact member along one side and with which the push button may engage. In such constructions, this last contact member may be bent over and serve as a spring for holding the battery at the end of the casing and preventing it from accidentally shifting toward the push button 21. It is, of course, evident that such spring contact would have to be insulated from the outer casing.

Although my improved device is prima-

rily intended to be worn by automobilists and for use as a signal, yet it will of course be evident that it may be used for various other purposes.

Having thus described my invention, what I claim as new and desire to secure by Letters Patent is:

1. In combination, a two-part casing, said parts having telescoping peripheral walls, a strap for holding said parts together and for securing said casing in position, an electric light carried by the outer wall of one casing part, and a push-button carried by the end wall of the other casing part, and a battery within said casing.

2. In combination, a casing adapted to be secured to and supported by the back of the hand, an electric battery therein, an electric light on the side of the casing away from the hand, and a plunger at the upper end of the casing and movable in the general direction of the length of the casing and adapted to be operated by engagement with the wrist upon a rearward bending of the hand in respect to the wrist to close the circuit.

3. In combination, a two part casing adapted to receive a battery, said parts having telescoping peripheral walls, a strap for holding said parts together and for securing said casing in position, an electric light carried by said casing, and a circuit closer therefor.

Signed at New York city in the county of New York and State of New York this 23d day of July, A. D. 1917.

LESTER PRAHAR.
